COATING MACHINE

Nicholas Pelosi, Newark, N. J., assignor to American Can Company, New York, N. Y., a corporation of New Jersey

Application November 23, 1940, Serial No. 366,921

2 Claims.

(Cl. 91—55)

This invention relates to coating machines and the like for applying a coating such as paraffin wax to the surfaces of fibre containers and has particular reference to the manner of oscillating a freshly coated container while it travels through a treating chamber of the machine wherein the coating is set evenly on all surfaces of the container.

In the manufacture of coated fibre milk containers of the character disclosed in United States Patent 2,085,979, issued July 6, 1937, to J. M. Hothersall, the container is preferably immersed in a bath of molten paraffin wax so that the interior and exterior surfaces of the container are thoroughly covered. After such a coating operation the excess wax is usually drained away and the container is then conveyed through a treating chamber to set and harden the applied coating.

An object of the invention is the provision of a continuous coating machine having a heated compartment wherein molten paraffin wax or the like is applied to all surfaces of fibre containers being coated, after which the freshly coated containers are transferred into a treating chamber and propelled therethrough upon a conveyor while they are simultaneously oscillated from side to side to evenly distribute the molten paraffin upon the walls of the container as the wax is setting.

Another object of the invention is the provision of such a coating machine wherein the freshly coated containers are conveyed through a treating chamber and guided along their path of travel by twisted tracks which cause parts of the conveyor to deviate from a straight path and thereby oscillate the containers sidewise to insure an even distribution of the coating material on all surfaces of the container as it is solidified.

Another object of the invention is to provide a machine of the above character wherein a coated container is supported by a carrier or cage and guided by a bar along devous paths of travel while such a cage and guide bar engage the coated container wall with a minimum of contact so as not to interfere with even distribution of the coating for substantially the entire body of the container.

Numerous other objects and advantages of the invention will be apparent as it is better understood from the following description, which, taken in connection with the accompanying drawings, discloses a preferred embodiment thereof.

Referring to the drawings:

Figure 1 is a plan view of a container coating

and treating machine embodying the present invention, parts being broken away and parts being shown in section;

Fig. 2 is a longitudinal section taken substantially along the broken line 2—2 in Fig. 1;

Fig. 3 is a transverse sectional view taken substantially along the broken line 3—3 in Fig. 1;

Fig. 4 is a top plan view showing the twisted rails and guide bar for imparting the oscillation to the container, parts being broken away;

Fig. 5 is an enlarged transverse section of the twisted tracks and guide bar taken substantially along the line 5—5 in Fig. 4 and showing a cage for supporting a coated container in one position of its oscillation; and

Fig. 6 is a view similar to Fig. 5 but taken substantially along the line 6—6 in Fig. 4 and showing another position of oscillation.

As a preferred embodiment of the present invention the drawings illustrate the principal parts of a coating and treating machine adapted for applying a coating of paraffin wax or the like to a fibre milk container of the character previously referred to or to other types of containers.

25 A container of the type referred to is indicated in the drawings by the latter *a* and is provided with a closing element *b* (Figs. 1, 2 and 3) which is hingedly secured to the container top by a wire staple. The closing element is arranged to fit in part into and to close a filling and dispensing opening *c* located in the top wall of the container when it is sealed for shipment or storage.

The containers *a* enter the machine in a horizontal position in continuous processional order (as at *A*, Fig. 2) and are fed by a continuously moving coating conveyor *B*. The coating conveyor carries the containers with their closing elements open, through a coating chamber *C* and then down into a bath of suitable coating liquid, preferably molten paraffin wax which is contained in a tank reservoir *D*. After immersion into the paraffin bath the conveyor carries the containers back over the top of the reservoir, 40 while turning them into an inverted position, to permit complete draining of excess paraffin from both the interior and exterior surfaces of the container.

45 When the containers are fully drained they are rotated over the top of the conveyor *B* to the opposite side and set on end in an upright position (as at *E*, Figs. 1 and 3). Adjacent the entrance end of the machine the coated containers are transferred from the coating conveyor *B* to a treating conveyor *F* (Figs. 1 and 3).

The treating conveyor F passes into a treating chamber G wherein filtered and substantially sterile air at a chilling temperature is continuously circulated. While traveling through this chamber and before the paraffin wax is fully set and hardened the containers are subjected to a sidewise oscillating movement so that the coating is evenly distributed on all surfaces of the container as it is also simultaneously filled with a charge of filtered and substantially sterile air.

Immediately following the oscillating movement and the charging with sterile air, each container is closed by having the hinged closure element b swung in so that its stopper part enters into the container opening. Continued chilling of the containers completely sets the paraffin coating and thereby seals the inserted part of the closure element thus trapping the charge of filtered sterile air inside of each container. This completes the coating and closing operation and the containers are thereafter discharged from the machine. The containers coated in this manner are moisture-proof and when sealed their inner coated surfaces are protected and kept free from contamination and in a hermetic condition prior to delivery to the dairy or other packer.

The various operating parts of the machine are entirely enclosed by plates of cast and sheet metal which in themselves constitute a part of the framework of the machine. These plates are in turn secured to a main frame 11 and the plates and main frame are supported by leg sections 12 (Figs. 1, 2 and 3).

A container feeding device is located at one end of the machine which is arranged to receive containers from an outside source and to feed them individually into spaced angular pockets 13 of a turret 14. The turret is rotated in timed relation to other moving parts of the machine. Such a container a is shown at the right of Fig. 2 as it is being transferred from a turret pocket 13 into a spaced receiving pocket 15 on the coating conveyor B.

The coating conveyor B which receives the containers to be coated extends the full length of the machine. The pockets 13 in the turret 14 and the receiving pockets 15 in the conveyor B are arranged to receive the containers in a horizontal position. The length dimension of the containers extends transversely of the machine. Fig. 2 of the drawings shows the top end of the container a with the closure element b in an open position with part of the opening c exposed.

The coating conveyor B comprises a plurality of V-shape buckets 16 (Figs. 1, 2 and 3), which are semi-circular in cross section and which are connected together by pairs of links to form an endless chain. This conveyor travels over and is driven by chain sprockets located at opposite ends of the machine.

A main drive chain sprocket 17 is mounted on a horizontal conveyor drive shaft 18. This shaft is journaled in bearings 19 formed in the wall of a conveyor housing 22 which is supported on legs 12 of the machine. The inner end of the drive shaft 18 carries a spur gear 23 through which suitable driving power may be imparted to rotate the shaft in proper time relation with other moving parts of the machine.

The conveyor B is guided in a straight path of travel by an upper guide track 24 and a lower track 25. These tracks are secured to vertical brackets 26 (Fig. 2) formed on cross beams 27, the ends of which are supported on the main

frame 11. The upper track 24 is mounted so that the upper run of the conveyor will be substantially horizontal, while the lower track 25 is inclined downwardly to direct the lower run of the coating conveyor down into the paraffin tank D.

The paraffin tank D extends nearly the full length of the conveyor B and is preferably made of sheet metal supported on angle irons secured to the legs 12 of the machine. Above the tank a sheet metal drip or splash pan 28 is provided and forms an upwardly flaring extension of the tank side walls. Liquid such as molten paraffin is introduced and contained in the tank in any suitable manner.

A steam jacket 29 is formed to surround the bottom and side walls of the tank. The outer walls of the steam jacket are in spaced relation to the tank walls. The paraffin in the tank is maintained in a molten condition at a predetermined temperature by steam which is circulated through the spaces between the tank and the jacket wall. A steam inlet pipe 31 is connected to the jacket wall to conduct steam into the jacket space from a suitable supply source. The molten paraffin in the tank D also heats the coating chamber C through which the containers a are transferred by conveyor B. This tends to pre-heat the containers a prior to being coated.

Proper advancement of the container a is effected by suitably spaced and parallel guide bars 32 (Figs. 1 and 2). These guide bars are supported at intervals along the conveyor by brackets 33 secured to the conveyor housing 22. A guide bar 34 is positioned adjacent the guide bars 32 and is also supported by the brackets 33. Guide bar 34 keeps the closure element b of a container a in open position as it is being transferred downwardly into the paraffin coating tank.

The entire container is submerged in the paraffin as it proceeds along its path of travel and the molten paraffin enters the container through its open dispensing hole c. The guide bars also guide the wax covered container as it travels upwardly out of the paraffin and as it passes around the sprocket onto the upper run of the conveyor. Preferably, somewhere along this run the guide bars are twisted so that the coated container may be rocked and drained, then turned into upright position while being carried along in the V-shaped conveyor pockets.

The turning and rocking motions thus imparted to a container partially filled with molten paraffin wax results in an even spreading of the wax inside of the container and also over any surfaces not previously covered. This also evenly spreads the molten wax on the exterior surface. Thus the entire container including its closing element is entirely and smoothly covered with paraffin wax. The moving containers are maintained in an inverted position while they travel back along the upper run of the conveyor for a predetermined distance so that the excess paraffin may drain off.

Following the draining period, the containers are rotated upon the semi-circular buckets 16 into an upright position, i. e., seated upon the bottom end. Upper guide bars 35 are provided to further guide the container along its path of travel while in an upright position. A separate guide bar 36 which is parallel to and spaced apart from guide bars 35 continues to hold the closure element b in open position. The guide bars 35, 36 are supported by brackets 37 which are secured to the conveyor housing 22.

The coated containers are now carried back toward the container entrance end of the machine where they are discharged from the conveyor B by a transfer device which is best illustrated in Figs. 1 and 3 of the drawings. This transfer device includes a rotatable turret 38 which is mounted on a vertical shaft 39 journaled in bearings 42 formed in a lower web section 43 of the main frame and in a cover plate 44 which is secured to an upper web section 45.

At the upper end the shaft 39 carries a spur gear 46 which meshes with and is driven by a gear 47 mounted on the upper end of a vertical drive shaft 48. The drive shaft 48 is journaled in bearings 49 formed in the web sections 43, 45 and in a lower cover 52 secured to a depending portion of a web section 53. At its lower end, the drive shaft 48 carries a gear 54 which is suitably driven by the main drive of the machine.

The transfer turret 38 is provided with a plurality of V-shaped pockets 55. A turret pocket comes into alignment with a coated container *a* in a bucket 16 of the conveyor B and receives such container from the conveyor. A curved guide plate 56 disposed adjacent the periphery of the transfer turret retains the containers in their turret pockets as the turret rotates. The bottom guide bar 35 and also the closure holding guide bar 36 extend beyond the other guide bars 35 and are coextensive with the guide plate 56. Accordingly the containers are retained in an upright position while they are being transferred by the turret.

The containers are also held against upward displacement during their movement with the transfer turret. For this purpose a plurality of horizontal fingers 57 (Fig. 3) are provided, one such finger being disposed over the top of each pocket. The fingers are pivotally mounted and are formed with two angularly disposed prongs 58 which are adapted to bear down and rest on the top of the container. Each arm carries a cam roller 59 which traverses a cam groove 62 of a stationary cam 63 secured to the cover plate 44 of the machine frame. It is the angular prongs 58 of the fingers that rest on the containers as the turret 38 transfers the containers onto a treating conveyor F. This conveyor moves in time with the transfer turret.

Conveyor F is parallel with and adjacent to the coating conveyor B and includes an endless chain (Figs. 1 and 3) which moves in a horizontal plane on spaced sprockets located in suitable manner. One of the sprockets is shown in the drawings designated by the numeral 64. It is mounted on and driven by the shaft 48.

At spaced intervals of the treating conveyor chain, container cages 65 are provided. Each conveyor cage is adapted to receive a coated container *a* and to support it in a vertical position. The container does not present a flat side to the front but is in angular position during its advancement so that one corner is the leading edge. Two lower prongs 66 of the cage contact the lower edge of the container while two side prongs 67 are arranged to engage the side walls of the body. The engaging prongs are designed so that they touch the container in a minimum surface contact so as not to mar the exterior coating of the container.

The back wall of the container cage 65 is adapted to be connected to links of the conveyor chain and two laterally extending arms 68 are provided (Figs. 1, 3, 5 and 6) for the purpose. Intermediate link sections 69 properly space ad-

jacent container cages. A roller 72 is inserted between the two arms 68 and provides for engagement with the teeth of the sprocket. A pin or stud 73 secures the arms together and the chain roller is mounted on the pin. This constitutes a non-friction roller chain for the conveyor.

The treating conveyor F travels through a treating chamber of the machine and it is here that the coated containers *a* are treated. In order to maintain the conveyor generally in a horizontal plane and further steady the cages with their containers, upper and lower guide tracks 74, 75 are used. Upper and lower rollers 76, 77 are mounted at the back of the container cages and are arranged to operate in the spaced apart upper and lower guide tracks.

At the top, cage 65 is formed with a lug 78 which supports a stud 79. Roller 76 is rotatably mounted on the stud and travels within a groove 81 of the upper guide track 74. The lower roller 77 is rotatably carried upon a laterally extending stud 82 secured to the lower back wall of the cage 65. The roller 77 is formed with spaced annular flanges 83 which straddle a center section or shoulder 84 on the lower track 75 and keep the roller on its track.

The upper and lower tracks 74, 75 (Figs. 1 and 4) extend as a straight section into the treating chamber G and are then in vertical alignment. At a junction point just inside the treating chamber, the upper track 74 is twisted inwardly and the lower track 75 is twisted correspondingly outwardly for the purpose of deviating the course of the container cage travel and this results in shifting the container *a* sidewise as it is carried along by the conveyor (Fig. 5). As the conveyor further advances the container, the cage which holds the container is shifted back in the opposite direction passing through its vertical position and this brings the container to the opposite side or into the position shown in Fig. 6. From this position a further twist in the tracks 74, 75 brings the container into a final vertical position, when the upper and lower tracks are again in vertical alignment.

The paraffin coating on the container *a* gradually changes from a molten state into a set condition as the container is subjected to this oscillating movement while traveling through the treating chamber. These oscillations therefore tend to distribute the paraffin evenly upon all surfaces of the container. Such even distribution is particularly desirable for the interior surface of the bottom wall of the container since this is a place most likely for the paraffin to accumulate. The end seam region is also likely to be a vulnerable part which requires special attention to insure a liquid-proof joint.

The upper and lower tracks 74, 75 are supported by brackets 86 secured to a vertical wall 87 of the treating chamber G at opposite ends of the machine. A guide rail 88 (Figs. 1, 4, 5 and 6) is spaced from and is parallel to the upper track and retains each container *a* within its cage as it is oscillated through the various positions along its path of travel. This guide rail is supported by a bracket 89 secured to the vertical wall 87 of the treating chamber.

The filming and solidification of the paraffin goes on while substantially sterile air is introduced into the chamber to contact with the containers. The container coating is just setting and the container is reaching the end of its travel

when the closing element *b* is pressed down into the sterile airfilled container. This closing element is sealed by the paraffin which fully sets as the container is being discharged from the machine. The containers are thus in proper hermetically sealed condition to be delivered to a customer.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for coating containers with paraffin and the like, the combination comprising means for applying an excessive amount of coating material to containers, means for draining substantially all excess coating material from said containers, a setting course whereon congelation is effected of coating material remaining on the walls of said drained containers, a conveyor operable along said course, cages secured to and movable with said conveyor and adapted to receive containers from said draining means, each of said cages being provided with prongs adapted to support with minimum contact a coated and drained container, parallel upper and lower track sections adjacent said conveyor and having twisted portions along said course, guiding devices substantially parallel to said twisted track portions for retaining the containers within said

35

cages when moving along said course, and rollers mounted on said cages and operable on while positively constrained by said tracks to support and guide the moving cages whereby oscillation back and forth of said cages and containers therein is effected by said twisted track to distribute said coating evenly while setting on the walls of said containers.

2. In a machine for coating containers with paraffin and the like, the combination of means for applying an excessive amount of coating material to containers, means for draining substantially all excess coating material from said containers, a setting course wherein congelation is effected of coating material remaining on the walls of said drained containers, a conveyor operable along said course, container holding means secured to and movable with said conveyor and adapted to receive containers from said draining means, parallel upper and lower track sections disposed adjacent said conveyor and having twisted portions along said course, guiding devices disposed substantially parallel to said twisted track portions for retaining the containers within said holding means when moving along said course, and means mounted on said holding means and operable while positively constrained by said track sections to support and guide said moving holding means, whereby oscillation of said holding means and containers therein is effected by said twisted track to distribute said coating evenly while setting on the walls of said containers.

NICHOLAS PELOSI.
